UNITED STATES PATENT OFFICE.

JOSEPH F. PROSSER, OF CLEVELAND, OHIO, ASSIGNOR OF ONE-HALF TO LOUIS CAUL,
OF CLEVELAND, OHIO.

HYDRAULIC MOTOR.

1,026,177.

Specification of Letters Patent.

Patented May 14, 1912.

Application filed May 18, 1909. Serial No. 496,736.

To all whom it may concern:

Be it known that I, JOSEPH F. PROSSER, a citizen of the United States, residing at Cleveland, in the county of Cuyahoga and State of Ohio, have invented a certain new and useful Improvement in Hydraulic Motors, of which the following is a full, clear, and exact description, reference being had to the accompanying drawings.

10 My invention relates to hydraulic motors and more particularly provides an efficient valve mechanism for permitting the inflow and outflow of water to and from the opposite sides of the piston of the motor.

15 Generally speaking, the invention comprises the elements and combinations thereof set forth in the accompanying claims.

Reference should be had to the accompanying drawings forming a part of this 20 specification, in which—

Figure 1 is a front elevation of a hydraulic motor shown in connection with a pump; Fig. 2 is a central vertical section through the hydraulic motor and valve mechanism; Fig. 3 25 is a side elevation of the casing containing the valve mechanism; Fig. 4 is a top plan view of the casing containing the valve mechanism with the motor casing removed; Fig. 5 is a central longitudinal section 30 through the valve casing, and Fig. 6 is an elevation partly in section of the valve casing and valve mechanism of the side opposite that shown in Fig. 3.

The hydraulic motor herein shown and 35 described, while shown in connection with and for the purpose of operating the pump, is not necessarily limited to such operation, and I do not intend to so limit it, the pump being shown merely to indicate a single use 40 to which the motor may be put.

In Fig. 1 a pump is indicated at 1 having an inlet pipe 2 and an outlet pipe 3. Within the pump is a piston 4 which is mounted upon a piston rod 5. The pump is joined 45 to the hydraulic motor by means of a frame 6 which is securely held upon the motor cylinder 7 by means of a nut 8, which engages a threaded portion upon said cylinder. Within the cylinder 7 is a piston 8 that is 50 mounted upon a piston rod which, as shown, is a continuation of the piston rod 5 and is connected with the piston 4 within the pump. However, as previously indicated, that portion of the piston rod which extends 55 outside the motor cylinder may be

used to operate any desired mechanism. Upon one side of the cylinder 7 is a duct 9 formed in the side wall thereof, which communicates through a port 9^a at the upper end with the interior of the cylinder, the 60 lower end of the duct 9 being open and communicating with the interior of the valve casing. The cylinder 7 is mounted upon a valve casing, the top part of which forms the bottom closure for the cylinder. This 65 casing comprises two parts 10 and 11 which extend at right angles to each other, the interiors of which parts are in communication one with the other. A pipe 12 communicates with the interior of the casing 10 for 70 the purpose of conducting water into the interior thereof, and a pipe 130 communicates with the lower part of the casing 11 forming an outlet for the water. Upon the interior, the casing 10 is provided with a 75 smooth cylindrical bore within which are mounted a series of tubular sections indicated at 13, 14, 15 and 16. Between the said tubular sections are spaces or openings indicated at 13^a, 14^a, and 15^a, the spaces 13^a 80 and 15^a being of the same size. These openings form ports for the ingress and egress of water.

Coöperating with the interior walls of tubular sections is a plunger which comprises a tubular member 17 formed with flanges 18 and 19. Coöperating with these flanges are packings 20 which are held in place by means of nuts 21. The packings 20 are curved around the shoulders so as to 90 engage with the internal side walls of tubular section and form a tight joint therewith.

The interior of the body portion 17 of the valve is hollow and through the same extends a rod 22 which at its lower end is threaded upon a cap nut 22^b, which in turn is threaded upon the lower end of the valve body 17. The rod 22 extends into the interior of the cylinder 7, being guided in its 100 reciprocation by an opening in a nut 23, which nut is screwed into one end of the opening within the casing 10. A suitable packing 24 is provided which is held in place by means of a gland nut 25.

The lower end of the piston rod 5 is hollow forming a tubular recessed portion indicated at 5^a. Into this hollow portion the rod 22 extends and at its upper end the rod is provided with a head 22^a for a pur- 110

pose later explained. The lower end of the piston rod 5 is engaged by means of a cap nut 5^b which holds the members of the piston in proper position upon the rod and is 5 also provided with an opening therethrough of sufficient size to permit the rod 22 to pass but small enough to prevent the head 22^a from passing. The lower end of the casing 10 is provided with a nut 26 which closes 10 the same.

The casing 11 is interiorly cylindrical and is encircled by a series of channels 28, 29, 30, 15 31 and 32 which are formed in the wall of said casing. The channel 30 is in communication at one portion thereof with the interior of the casing 10, the communication being by means of the space or port 14^a, indicated in Fig. 2. Within the interior of the casing 11 are a series of tubular sections separated from each other, thereby providing 20 spaces or ports 32^a, 31^a, 30^a, 29^a and 28^a, which spaces or ports are in communication with the ducts 32, 31, 30, 29 and 28, respectively. Within the casing and coöperating 25 with the spaced tubular sections before mentioned, is a valve comprising a cylindrical central portion 33 having thereon disks or pistons 34, 35, 36 and 37, which have a working fit with the tubular sections. The opposite ends of the casing are closed by means 30 of nuts 38.

The interior of the casing 10 is in communication with the opposite ends of the casing 11 by means of ducts 39 and 40, as illustrated in Figs. 3 to 5 inclusive. The duct 39 is in communication with the space or opening 13^a, while the duct 40 is in communication with the space or opening 15^a which are within the casing 10. It will thus be apparent 40 that when the valve within the casing 10 is in position to permit water to enter through the port 13^a this water will, by passing through the duct 39 enter the casing 11 behind the piston 37, and on the other hand, when the valve within the casing 10 is at the opposite end of its reciprocation and water is permitted to pass through the port 15^a, the water will pass through the duct 40 and enter the space behind the piston 34. 45 In this manner the valve within the casing 11 will be caused to reciprocate within its casing at the same time that the valve within the casing 10 is reciprocated.

The duct 31 is in communication with a 55 conduit 41, shown in Fig. 6 and in Fig. 2, which conduit at its upper portion coöperates with the channel 9 formed in the wall of the cylinder 7. The duct 29 is in communication with a conduit 42, shown in Fig. 6, 60 which conduit communicates with the interior of the casing through a port hole 46 formed in the bottom of the cylinder 7, which as heretofore described, is the top of the valve casing. The conduits 32 and 28 65 are provided at their lower portions with

outlets 43 and 44, respectively, which communicate with a water exit chamber 45. This chamber is in communication with the outlet pipe 130, which pipe conducts the water away.

The operation of the motor is as follows: In the position shown in Fig. 2, water is being admitted above the piston 8 so that the same is descending within the casing 7 toward the lower part thereof. In the position shown, the valve within the casing 11 is at the extreme limit of its reciprocation in one direction, and in the position shown the valve has uncovered the port 13^a so that water entering through the pipe 12 and 70 through the port 14^a may also pass through the port 13^a, thence through the conduit 39 to the rear side of the position 37. Consequently the valve within the casing 11 is held at the limit of its reciprocation in one direction 75 by the water pressure behind the piston 37. The water may also enter within the casing 11 by means of the port 30^a, and as shown, the valve within the casing 11 is in such position that the piston 35 has uncovered the 80 port 31^a. The water may accordingly enter through port 31^a, thence through duct 31, through conduit 41, duct 9 and port 9^a into the interior of the cylinder 7 above the piston 8, causing the piston to descend. The 85 length of the recess 5^a within the end of the piston rod 5 is such that it will engage the head 22^a upon the rod 22 just before the piston 8 completes its stroke, and will push the rod 22, so that it will occupy a position at 90 the lower end of the casing 10, in which position the port 13^a will be closed to the inlet water by means of the packing 20 and the port 15^a will be open to communication with the water coming through the pipe 12 by 95 virtue of the fact that the valve has moved below the port 15^a. When this takes place, the water entering through the pipe 12 and port 14^a will pass through the port 15^a, thence through the conduit 40 to the space 100 behind the piston 34 exerting a pressure thereon and causing the valve within the casing 11 to reciprocate to the opposite end of the casing. It will be noted that when the valve within the casing 10 has reciprocated to the opposite end of the casing the port 13^a will be above the nut 21, therefore the water which was confined behind the piston 37 and within the duct 39 will, upon the reverse reciprocation of the valve 105 within the casing 11 be forced into the space within the casing 10 which is above the nut 21. This water will flow through the interior of the valve body 17, through the ports 17^a, and drop to the lower portion of the casing 10, flowing out through the port 10^a into the chamber 45, from whence the water will be conducted through the waste pipe.

The reciprocation of the piston within the chamber 11 just described, will cause 110

- the piston 35 to pass beyond the port 31^a, closing the same to inlet water, and will also cause the piston 36 to pass beyond the port 29^a, so that water passing through the port 30^a will have egress through the port 29^a to the duct 29, thence through the conduit 42 and port 46 to the interior of the casing 7 upon the under side of the piston 8, thereby producing pressure upon this side 5 of the piston and causing it to reciprocate toward the opposite end of the casing. The reciprocation of the valve within the casing 11 will carry the piston 35 to a point so that the rear portion of said piston will 10 just pass the duct 31^a. However, the piston 34 will not reciprocate far enough but that the duct 32^a will still be uncovered. It will therefore be apparent that the water which has previously been confined above the piston 15 20 will now pass through the port 9^a, duct 9, conduit 41, duct 31, port 31^a, port 32^a into the duct 32, from whence it will flow through the outlet port 43 into the chamber 45 and thence be conducted through 25 the waste pipe. When the piston 8 within the casing 7 approaches the end of its opposite reciprocation, the nut 5^b will engage with the head 22^a upon the rod and will pull the rod 22 so that the valve within the 30 casing 10 is returned to the position shown in Fig. 2, under which circumstances the valve within the casing 11 will be reciprocated to the position shown in Fig. 5, and the water will be admitted to the upper side of 35 the piston 8, causing the said piston to descend. Under these circumstances, the water within the lower part of the casing, will pass through the conduit 42 to the duct 29, thence through the port 29^a and port 28^a 40 to the duct 28, and then through the outlet port 44 to the interior of the chamber 45, and thence will pass through the waste pipe 130. The water which was behind the piston 34 will pass through the conduit 40 and 45 through the port 15^a into the interior of the lower part of the casing 10 and thence through the port 10^a to the chamber 45 and through the waste pipe 130. It will be apparent from the above description, that the motor herein shown and 50 described may be operated from a single source of water and will automatically reciprocate as long as the water is allowed to flow. Attention is further directed to the 55 tubular sections within both parts of the valve casing. The desideratum in valves of this class, is to afford large opening for the passage of fluid and yet one which may be quickly and completely closed. Continued 60 flow of water under pressure after the reversal should take place is very undesirable because it makes the motor slow and the successful control of the water must be obtained through quick acting valves. 65 The ports in the valves here shown are of large area for the passage of water, yet the space between the adjacent sections is not very great and, therefore, the closing piston may very quickly cover the same and so almost instantly shut off the flow of 70 water or permit the flow, as the case may be. A further important result of the construction I have herein disclosed, lies in the fact that the dead water, that is the water which is about to flow out from the casing 75 due to the reversal of the motor, will flow out by its own gravity and will not require to be pumped or forced out. When water is being forced into the casing below the piston, the valve in the casing 11 will be in 80 proper position so that the water from the interior of the casing may flow through passages 9 and 41 and so to the waste pipe. It will be noted that the passages 9 and 41 are filled with water at the time the reversal takes place, and further it will be noted that the combined passages 9 and 41 are longer than the depth of the casing, therefore a siphon effect is produced which removes all the water from above the piston 85 without any help from the piston. In fact, if anything, the siphon effect assists the travel of the piston. Conversely when the live water is flowing into the top of the casing, the dead water below the piston flows 90 by gravity to the waste pipe. When the motor is placed in a horizontal position, it is placed in such position that the ports 10 and 46 are at the lowest part of the structure so that the weight of the dead water will 95 100 still cause it to flow out. I do not limit myself to the exact construction shown except in so far as the wording of the claims expressly does so. Having thus described my invention, what 105 I claim is:
1. In a device of the character described, a cylinder, a piston within said cylinder, water inlets to said cylinder, a valve cylinder associated with said cylinder, a valve in said casing controlling the passage of water to said cylinder, a cylindrical opening in the valve casing, tubular sections within said opening, said tubular sections being spaced apart to form ports, one of said ports communicating with the first-mentioned valve, ducts 110 communicating with other ports for conducting water to the opposite ends of the first-mentioned valve, a water inlet pipe communicating with all the ports in the cylindrical opening, a valve provided with heads which engage with the tubular sections in the casing, and means for operating said valve to successively open and close the ports which govern the supply of water to 115 the opposite ends of the first-mentioned valve. 120
  2. In a device of the character described, a cylinder having a piston therein, water inlets to said cylinder, a valve casing associated 130

with said cylinder, a valve in said casing governing the supply of water to the interior of said cylinder, a cylindrical opening in said valve casing, a plurality of ports in said opening, one of said ports communicating with the valve which regulates the supply of water to the first-mentioned casing, the other ports controlling the supply of water to the opposite ends of the first-mentioned valve for operating the same, a valve plug in said cylindrical opening for successively opening and closing the ports which govern the supply of water to the opposite ends of the first-mentioned valve, said plug being hollow, whereby the waste water from one end of the first-mentioned valve may flow through the same.

3. A hydraulic motor comprising in combination a cylinder, a piston within said cylinder, water inlets to said cylinder, a valve casing associated with said cylinder, a valve in said casing controlling the passage

of water to said cylinder, a cylindrical opening in the valve casing, a tubular lining within said opening, said tubular lining having spaced ports therein, one of said ports communicating with the first mentioned valve, ducts communicating with other of said ports for conducting water to the opposite ends of the first mentioned valve, a water inlet pipe communicating with all the ports in the tubular lining, a valve provided with heads engaging said lining and adapted to govern the passage through the ports therein, and means for operating said valve to successively open and close the ports which govern the supply of water to the opposite ends of the first mentioned valve.

In testimony whereof, I hereunto affix my signature in the presence of two witnesses.

JOSEPH F. PROSSER.
